COMPRESSOR UNIT

Jens A. Passche, Wilmette, Ill.

Application August 15, 1930, Serial No. 475,466

3 Claims. (Cl. 230—58)

The invention relates generally to compressing mechanism for gaseous fluids and more particularly to compressors of relatively small size and weight capable of being carried or otherwise transported from place to place.

An object of the invention is to provide a novel unit for creating and supplying compressed gas which is complete in itself, is relatively light in weight, and compact in arrangement of parts, and which is capable of providing a clean, dry and cool supply of gas, such as air, under pressure.

Another object of the invention is to provide an improved unit for producing cool, dry gas under pressure which unit includes a means for compressing the gas, means for separating water, oil and other foreign matter from the compressed gas, and a conduit connecting said means arranged to cool the gas passing therethrough.

In the operation of gaseous fluid compressors, it is well-known that a large amount of heat is created by the compression of the gas, which heat is transmitted to the machine as a whole. Consequently, after such machines have been in operation only a short length of time they become very hot and cannot be touched by the bare hand.

A further object of the present invention is to provide, in a mechanism of this character, new and improved means for moving the mechanism about, which means is automatically maintained at a low temperature by the operation of the mechanism.

More specifically stated, an object of the invention resides in the provision of a tubular member, which may be a silencer unit for eliminating noise incident to the operation of compressors, connected to the intake side of the compressor and forming all or a part of a conduit through which the gas passes to the compressor, said tubular member being fashioned as a handle for the grasp of an operator so that the flow of gas therethrough automatically maintains the temperature of the handle at a relatively low and constant point which is substantially less than that of the rest of the assembly.

Other objects and advantages will be apparent in the following description and from the accompanying drawing, in which:

Figure 1 is a side elevation of a unit embodying the features of the present invention.

Fig. 2 is a longitudinal central section on an enlarged scale of the oil and water separator assembly.

Fig. 3 is a longitudinal central section on an enlarged scale of the air-cooled silencer handle.

Fig. 4 is a modified form of unit showing a silencer employed as a handle on a small compressor unit.

In disclosing the present invention I have chosen, for illustrative purposes, to show the features thereof as being embodied in an organization especially adapted for use in connection with an apparatus for applying paint or color by air-brush or similar pressure-painting or spraying device. It will, of course, be readily apparent to one skilled in the art that many features of the invention are also applicable to uses other than in this particular adaptation.

Referring particularly to the drawing, 10 designates generally a gaseous-fluid-compressing mechanism of any well-known type and construction. That shown herein for illustration is a rotary air compressor 11 which is driven at a high speed by a motor 12, said motor and compressor being preferably combined, as shown, 75 into a unitary structure. Throughout the following description the term "gas" will be generally understood to be indicative of air or other suitable compressible fluid. The compressor includes a head 13 having an inlet 14 and an outlet 15 through which air is drawn into and ejected from the compressor. The constructional details of the compressor form no part of the present invention and will not, therefore, be given, it being deemed sufficient to say that the compressor is of such size and weight as to permit transportation thereof from place to place.

The motor and compressor may be mounted on means which facilitates transportation thereof from place to place. For this purpose, the 90 motor casing has a pair of spaced brackets 16 (only one of which may be seen in Fig. 1) depending from one side thereof. Each bracket mounts a suitable roller element 17, such as a pivoted caster. At the opposite end of the unit, the 95 compressor has a bracket 18 secured thereto which also carries a pivoted caster 19 or similar element. The roller elements 17 and 19 occupy positions conforming to the apexes of a triangle to support the unit.

The means by which oil, water and other deleterious foreign matter are removed from the compressed gas may be of any well-known construction. The separator which is shown herein is designated generally 20 and comprises (see 105 Fig. 2) an elongated tubular casing 21 having near its lower end a transverse, foraminous partition or wall 22 dividing the casing into a large upper compartment and a small lower compartment. The upper compartment is filled with 110

closely packed material, such as the diagrammatically indicated brass coils 23, by which a separation of oil and water from the gas is produced.

5 The ends of the casing are closed by upper and lower heads, designated 24 and 24^a respectively. The lower head 24^a preferably has a pet-cock 24^b thereon through which the accumulation of the separated oil and water may be drained. The upper head 24 is tapped to receive a suitable inlet fitting 25 to which a pressure gauge 26 of customary design may be connected. The fitting 25 within the casing communicates with a short foraminous member 27 through which 10 gas passes into the upper chamber. Subsequently, the gas flows downwardly of the chamber and passes through the foraminous partition 22.

From the lower chamber the gas is conducted 20 to the head 24 by a longitudinal duct 28 which extends from the lower chamber to an outlet port 29 in the head. If desired, a screen 30 or like member may be disposed about the open end of the duct 28. Any preferred type of nipple 31 25 (Fig. 1) and conduit 31^a may be connected with the port 29 for conveying the cleaned gas from the unit.

The separator 20 is mounted rigidly in any suitable manner, on a projecting shelf 32 (Fig. 1) 30 preferably formed as a part of the bracket 18, whereby the separator is positioned adjacent to the compressor.

As is well known, the application of pressure to a gas produces a large amount of heat so that 35 the compressed gas issues therefrom in a highly heated condition. In most paint spraying systems, a highly heated pressure gas is exceedingly undesirable. Consequently, means is provided in the instant unit for cooling the gas to a proper 40 temperature. In one form, this means comprises a conduit 33 in the shape of a helical coil arranged in surrounding relation to the separator. The conduit is preferably formed of a metal, such as copper, which is a good conductor of heat. 45 One end of the coil is connected to the outlet 15 from the compressor, and the other end has a straight extension 33^a which communicates with the inlet fitting 25. This arrangement is compact and in operation is very satisfactory. The 50 hot gas from the compressor flows to the separator through the coil 33 thereby reducing the temperature of the gas to a suitable point before it reaches the separator.

Incidental to the operation of a gas compressor 55 is an undesirable heating of the compressor parts which makes the unit difficult to handle during the operation thereof. The present invention provides a handle 34 for moving the compressor from place to place which is arranged to be automatically cooled by the flow of relatively cool 60 air to the intake 14. To this end, the handle is in the form of a tubular casing which communicates at one end with the intake to the compressor. The other end of the tubular casing is 65 open to atmosphere in the present instance but, of course, may be connected in any suitable manner with a source of gas to be compressed. Preferably, the intermediate portion of the handle is of a size convenient to be grasped and, while it is 70 not necessary, it is advantageous if this portion be positioned substantially above the center of gravity of the compressor.

Compressors of the type illustrated, which operate at a high rate of speed, produce, as an incident to their operation, a shrill noise which is 75

quite objectionable. I have, therefore, embodied in the tubular casing a means (which may be termed a silencer) for absorbing or muffling the noise. A suitable means for this purpose comprises (see Fig. 3) a plurality of sleeves 35 and 36 of different diameters mounted within the tubular handle. The sleeves are concentric with respect to each other and to the tubular member and define therebetween gas passageways 37 and 38. Helical partitions 39 and 40 in the passageways 38 and 37, respectively, define elongated spiral paths along which the gas must flow in order to pass from one end to the other of the tubular member. This circuitous path serves to baffle and absorb the noise produced with only slight frictional resistance to the free flow of air to the compressor, thereby rendering the operation of the compressor silent and unobjectionable.

In the operation of the unit, gas passing to the compressor is drawn through the tubular casing 95 34 connected to the intake passageway. This gas will ordinarily be at room temperature and will always be at a much lower temperature than that of the compressor. Consequently, the handle will automatically be maintained at a relatively low temperature. This is more especially true where the silencer-handle is employed since a large surface area is exposed to the cooling action of the inflowing fluid.

In Fig. 4 a handle of this character is shown 105 as applied to a small compressor unit 41 adapted to be carried from place to place in the operator's hand. In this modified form, the intake 42 for the compressor is located at one end of the unit. Hence, the tubular casing comprising the handle is bent, as at 43, to extend over the body of the compressor. A second silencer means 44 may be attached to the outlet passageway 45 to form a part of the conduit 46 leading from the compressor to produce a still more quietly operating 110 machine. Since the compressed gas passes therethrough in a highly heated condition, the silencer 44 preferably occupies an out-of-the-way position along the lower portion of the compressor. In the larger unit (Fig. 1) a second 120 silencer on the outlet may be employed but is usually not necessary because of the quieting effect of the cooling coil 33 and separator.

From the foregoing, it will be apparent that a handle of new and improved form has been provided for fluid compressing mechanism which is automatically maintained at a low temperature by the flow of fluid to the mechanism and at the same time embodies a silencing means for absorbing the noise of operation of said mechanism.

I claim as my invention:

1. A unit for producing compressed gas comprising, in combination, a unitary gas compressor and a motor for driving said compressor, said compressor having an inlet and an outlet for gas, 135 brackets connected to said motor having roller elements mounted thereon, another bracket carried by said compressor and having a roller element thereon, said roller elements being mounted for pivotal movement to facilitate transportation 140 of the unit, an oil and water separator, a platform carried by said last mentioned bracket for supporting said separator in a position adjacent said compressor, and a helically coiled cooling conduit surrounding said separator and connecting said compressor outlet with said separator for cooling the compressed gas during the passage 145 thereof from the compressor to the separator.

2. A compressing machine capable of operating upon gaseous fluid, and means for conduct-

ing said fluid to said machine including a tubular member connected to the intake side of the machine, said member being fashioned to be grasped by an operator to transport the machine 5 from one point to another, thereby providing a handle the temperature of which is maintained at a relatively low and constant point by the flow of fluid therethrough.

3. The combination of a gas-compressing 10 mechanism having an inlet thereto through which

gas to be compressed flows to the mechanism, and a tubular unit rigidly connected to said inlet for conducting gas thereto and including means for quieting noise incident to the operation of the mechanism, said unit being formed as a handle for the assembly which is maintained at a lower temperature than that of the mechanism by the flow of gas therethrough. 80
